UNITED STATES PATENT OFFICE.

STERLING B. FRANKLIN AND GAVIN S. YOUNKIN, OF ARKANSAS CITY, KANSAS.

LIGHT SHIELD AND REFLECTING DEVICE.

Application filed August 15, 1921. Serial No. 492,414.

To all whom it may concern:

Be it known that we, STERLING B. FRANKLIN and GAVIN S. YOUNKIN, citizens of the United States, residing at Arkansas City, in the county of Cowley and State of Kansas, have invented a certain new and useful Improvement in Light Shields and Reflecting Devices, of which the following is a specification.

10 Our invention relates to improvements in light shields and reflecting devices particularly well adapted for use on automobiles.

The object of our invention is to provide a novel light shield and reflecting device 15 which will prevent the reflection upwardly of the rays of a lamp mounted in an ordinary parabolic reflector, which will hide the lamp from view of a person standing a short distance away in front of the machine, and 20 which will reflect the obstructed rays of the lamp upon the parabolic reflector in directions such that they will be directed forwardly and downwardly by the parabolic reflector, thereby increasing the intensity of 25 the light which is projected on the ground in front of the machine.

Our invention provides further a device of the kind described which is simple, cheap to make, durable, not liable to get out of order 30 and which may be readily applied to lamps now in use.

The novel features of our invention are hereinafter fully described and claimed.

In the accompanying drawing which illustrates the preferred embodiment of our invention,

Fig. 1 is a front view, partly in vertical section, and partly in elevation and partly broken away of our improved light shield 40 and reflecting device.

Fig. 2 is a vertical sectional view of the line 2—2 of Fig. 1.

Fig. 3 is a horizontal section on the line 3—3 of Fig. 1.

45 Fig. 4 is a diagrammatic view illustrating the directions of travel of a ray reflected by the shield reflector and parabolic reflector.

Similar reference characters designate similar parts in the different views.

50 1 designates an ordinary parabolic reflector, such as is commonly used in connection with automobile lamps and which has a central opening in which is fitted an ordinary incandescent lamp 2 with its filament located substantially in the focus F, of the reflector 1, the latter having a concave reflecting sur-

face arranged to throw the rays of light forwardly and substantially in parallel lines.

Extending transversely across the front of the reflector 1 is the usual transparent glass plate 3 which is held in position by a ring 4, having a rearwardly extending annular flange 5, which embraces the periphery of the reflector 1, and which has a plurality of inwardly extending projections 6, adapted 60 to respectively enter notches 7 in the periphery of the reflector 1, and which are adapted to engage the rear side of the reflector when the ring 4 is turned to the proper position.

8 designates a gasket interposed between 70 the glass 3 and the reflector 1.

For obstructing the direct rays from the lamp 2, and the rays which would be reflected forwardly and upwardly by the lower half of the reflector 1, we provide a smaller 75 substantially semicircular reflector 9, which is mounted in the reflector 1 in front of the focus of the latter, and in front of the lamp 2, and which extends from a point adjacent to the horizontal plane of the upper side of 80 the lamp 2 downwardly and laterally across the axis of the reflector 1 to the reflecting surface of the latter.

The rear side of the reflector 9 is concave and is arranged to reflect rays which strike 85 it rearwardly against the concave reflecting surface of the reflector 1. The curvature and disposition of the concave reflecting surface of the reflector 9 are such that the major portion of the rays of light reflected by it will be finally reflected forwardly and downwardly by the reflector 1 over the upper edge of the reflector 9 which is spaced apart from the upper side of the reflector 1, and which is, preferably slightly above the 90 horizontal plane of the upper side of the lamp 2.

For supporting the reflector 9 in the reflector 1, so as to permit ready insertion or removal of the reflector 9, the latter has attached to its forward side at one point adjacent to the middle thereof a T-shaped member 10, the horizontal arms of which, as well as its vertical stem, are held between the glass 3 and the reflector 1. 105

In Fig. 4 is illustrated the directions of travel of a ray of light F—A passing from the lamp 2 to the reflector 9. From the point A, the ray of light passes to the point B on the reflector 1, thence to the point C 110 on the reflector 9, thence to the point D on the reflector 1, and from thence downwardly

and forwardly as indicated by the dotted line D—E.

From the above it will be understood that the reflector 9, while it serves as a shield for covering the lamp 2 and for preventing rays from the lower half of the reflector 1 from being projected forwardly and upwardly, so as to dazzle the eyes of a person standing or otherwise positioned in front of the machine 10 carrying the lamp, does not absorb the obstructed rays, but reflects them rearwardly against the reflector 1 in directions such that they are eventually directed against the ground in front of the lamp and add to the 15 illumination thereof by the rays which are reflected downwardly in the ordinary manner by the upper portion of the reflector 1.

We do not limit our invention to the structure shown and described, as many modifications within the scope of the appended claim, 20 may be made without departing from the spirit of our invention.

What we claim is:—

In a device of the kind described, the combination with the usual parabolic reflector, a 25 lamp therein, and a ring releasably engaging the reflector, of a second reflector located within the first and having a concave reflecting surface arranged to reflect light from the lamp against the reflecting surface 30 of the first reflector, which is below the lamp, and having its rear edge fitted to the reflecting surface of the first reflector, the second reflector extending to the horizontal plane of the top of the lamp, and a supporting plate secured to the second reflector and arranged to hold the rear edge of the latter against the first reflector and releasably held by the ring between the latter and the first 35 reflector, substantially as set forth.

In testimony whereof, we have signed our names to this specification.

STERLING B. FRANKLIN.
GAVIN S. YOUNKIN.
